UNITED STATES PATENT OFFICE.

JOHN BRUDZ, OF SCALP LEVEL, PENNSYLVANIA.

PLOW.

1,175,507.

Specification of Letters Patent. Patented Mar. 14, 1916.

Application filed May 12, 1915. Serial No. 27,538.

To all whom it may concern:

Be it known that I, JOHN BRUDZ, a subject of the Emperor of Austria-Hungary, residing at Scalp Level, in the county of 5 Cambria and State of Pennsylvania, have invented certain new and useful Improvements in Plows, of which the following is a specification.

This invention relates to new and useful 10 improvements in plows.

The primary object of the invention is the provision of a plow having a shiftable carriage arrangement for the plow beam and whereby a lateral adjustment thereof is 15 permitted during the forward operative movement thereof.

A further object of the invention is the provision of a floating plow beam shiftably resting upon the soil turning member and a 20 forward carriage for unitedly permitting the automatic adjustment of the several parts during the plowing operation.

With these general objects in view and others that will appear as the nature of 25 the invention is better understood, the same consists in the novel combination and arrangement of parts hereinafter fully described, illustrated in the accompanying drawings and pointed out in the appended 30 claims.

In the drawings forming a part of this application and in which like designating characters refer to corresponding parts throughout the several views:—Figure 1 is 35 a side elevation of the device. Fig. 2 is a top plan view thereof. Fig. 3 is a horizontal sectional view through the mold board and its frame, the plow shares being removed. Fig. 4 is a perspective view of the 40 mold board engaging nose or point, and Fig. 5 is the plow beam engaging bar.

Referring more in detail to the drawings, a plow beam 10 is provided having the forward end thereof freely engaging by reason 45 of its own weight upon a bearing bar 11 and within one of the transverse grooves 12 thereof, the said bar 11 being vertically adjustably mounted upon posts 13 carried by the axle 14 of ground engaging wheels 50 15. Pins 16 are connected to the posts 13 by means of chains 17, the said pins being adapted for reception through the perforations 18 of the bearing bar 11 and transverse perforations 19 of the said posts. A 55 draft tongue 20 is attached to the axle 12

for the purpose of drawing the plow forwardly during the operation thereof.

The plow beam 10 is provided with a plurality of notches 21 in its upper side adapted for the adjusted reception of a link 22, 60 which link is connected by means of a chain with the said axle 14 at a point normally beneath the said beam. Pins 24 are transversely arranged through the beam 10 slightly in advance of each of the notches 65 21 and the forward draft upon the tongue 20 imparting a pull upon the chain 23 forces the link 22 which is within one of the notches 21 against the adjacent pin 24 and in this manner the beam is fulcrumed more firmly 70 in one of the receiving grooves 12 while the beam is forwardly and longitudinally moved.

A hoe member or colter 25 is attached to the lower end of an arm 26 which passes 75 through a bracket 27 secured by means of straps 28 to the beam 10. An adjusting bolt 29 is designed for positioning through the desired one of the perforations 30 of the colter arm 26 and also through the beam 10 80 and whereby the colter is swingingly mounted at the desired elevational adjustment. Expansion springs 31 engage between one of the strips 28 and the adjacent face of the arm 26 for normally positioning the said 85 arm vertically. This vertical position will be maintained during ordinary work but upon a contacting of the hoe with any unusual obstruction, the springs 31 will allow the hoe to slightly relax, thus preventing the 90 hoe from being broken.

A mold board 32 is operatively positioned upon a ground engaging sliding base 33 and secured to an upright post 34 thereof by means of bolts 35. The plow beam 10 has a vertical opening 36 extending therethrough and adapted for the reception of the upper reduced end 37 of the aforementioned post 34, the said beam resting upon opposite curved shoulders 38 of the said post. 95 Springs 39 are arranged between the opposite sides of the post extension 37 and the adjacent end faces of the beam slot 36 for resiliently maintaining the beam in its rocking engagement upon the post 34.

Plow handles 40 are arranged with upper rearwardly extending ends 41 and having their lower curved ends 42 rockingly seated within opposite curved notch sockets 43 of the said base 33, a pivoted pin 44 ex- 110

tending through the said lower ends 42 and the base 33. The rear end of the plow beam 10 is freely positioned upon a cross piece 45 of the plow handles and the rearward sliding movement of the plow beam 10 thereon is limited by means of a projecting pin 46 carried by the beam. A spring 47 is secured adjacent the rear end of the base 33 and freely extends through an opening 48 in the rear end of the plow beam 10. A removable nose or point 49 is secured to the forward end of the mold board 32.

From this detailed description of the invention, it will be seen that the plow may be drawn forward by means of the tongue 20 through the agency of the chain 23 and the link 22, which latter is adjustably attached to the plow beam 10, the inclination of the said beam being regulated by means of the adjustable bearing bar 11. The plow beam 10 may be positioned in a desired groove 12 to hold the same in alinement with the tongue 20 when different drafting strains occur on opposite sides of the tongue. The hoe 25 is readily adjusted as may be found desirable while the mold board 32 is drawn forwardly by means of the post connection 34 with the beam 10, the beam being capable of rocking upon the said post and the plow handles being also slightly shiftable, it being noted that a chain 50 connects the upper rear corner of the mold board with the adjacent side of the plow handle. A serviceable plow being arranged, the forwardly impelling of the same allows the beam to adjust itself to any one of the bar grooves 12 in which the beam may automatically move. While the form of the invention herein shown and described is what is believed to be the preferred embodiment thereof, it is nevertheless to be understood that minor changes may be made in the form, proportion and details of construction without departing from the spirit and scope of the invention as set forth in the appended claims.

What I claim as new is:—

1. A plow comprising a wheel axle, upright posts carried thereby, a bearing bar removably mounted upon the said posts and having a plurality of grooves in its upper face, a plow beam having its forward end freely seated in a desired one of the said grooves and being provided with a plurality of notches in its upper side, transverse pins carried by the said beam adjacent the said notches, an adjustable link within one of the said notches in engagement with the adjacent one of the said pins, a connecting chain beneath the lower end of said link

and said axle, and a freely shiftable plow member arranged beneath the rear end of the said beam.

2. A plow comprising a wheel axle, upright posts carried thereby, a bearing bar removably mounted upon the said posts and having a plurality of grooves in its upper face, a plow beam having its forward end freely seated in a desired one of the said grooves and being provided with a plurality of notches in its upper side, transverse pins carried by the said beam adjacent the said notches, an adjustable link within one of the said notches in engagement with the adjacent one of the said pins, a connecting chain beneath the lower end of said link and said axle, the said beam being provided with a vertical perforation adjacent its rear end, a slide base, an upright post upon the said base having a reduced upper end freely positioned through the said beam opening and having opposite curved engaging shoulders beneath the said beam, a mold board secured forwardly of said base and post, and plow handles carried by the said base and shiftable attached to the said beam. 85

3. A plow comprising a wheel axle, upright posts carried thereby, a bearing bar removably mounted upon the said posts and having a plurality of grooves in its upper face, a plow beam having its forward end freely seated in a desired one of the said grooves and being provided with a plurality of notches in its upper side, transverse pins carried by the said beam adjacent the said notches, an adjustable link within one of the said notches in engagement with the adjacent one of the said pins, a connecting chain beneath the lower end of said link and said axle, the said beam being provided with a vertical perforation adjacent its rear end, a slide base, an upright post upon the said base having a reduced upper end freely positioned through the said beam opening and having opposite curved engaging shoulders beneath the said beam, a mold board secured forwardly of said base and post, the said base having oppositely arranged sockets, plow handles having curved lower ends pivoted within the said base sockets, a cross piece upon the said plow handles arranged beneath the said beam, a limiting stop pin carried by the beam forwardly of the said cross piece and a rearwardly arranged spring carried by the base and extending through the rear end of the said beam. 100 105 110 115

In testimony whereof I affix my signature.

JOHN BRUDZ.
